UNITED STATES PATENT OFFICE.

AUGUSTUS NEWELL, OF CHICAGO, ILLINOIS.

DESIGN FOR A KEY FOR MUSICAL INSTRUMENTS.

SPECIFICATION forming part of Design No. 23,166, dated April 3, 1894.

Application filed January 12, 1894. Serial No. 496,684. Term of patent 14 years.

To all whom it may concern:

Be it known that I, AUGUSTUS NEWELL, a citizen of the United States, residing at Chicago, in the county of Cook and State of Illinois, have invented and produced a new and original Design for Keys for Musical Instruments, of which the following is a specification, reference being had to the accompanying drawings, forming a part thereof.

My invention has relation to designs for keys for musical instruments, and relates particularly to those keys of piano and organ key boards which are termed "sharps."

The invention consists in the new and original shape or configuration of such keys as hereinafter particularly described in the specification and illustrated in the drawings.

In the accompanying drawings, Figure 1 represents a side elevation of my new and original form of key. Fig. 2 is a top view of the same. Figs. 3, 4, and 5 are bottom, front, and rear views respectively of such key.

A is the bottom face of the key. This is a substantially plane surface and has parallel lateral edges, A', A'.

B is the top face of the key. This is substantially horizontal in cross section at all points, but slopes downward from the front toward the rear and is narrower than the bottom face, A. Said face, B, has lateral parallel edges, B'.

C is the front face of the key. This I make sloping toward the rear from the bottom face, A, to the top face, B. The corners formed by the intersections of the planes of the faces, 35 B, and C, are reduced so as to form small faces, C', C', and leave the front of the face, B, and the upper portion of the face, C, rounded.

The rear face, D, has its lower edge perpendicular to the length of the key.

E E are the side faces of the key and occupy the space between the edges, A', and B'. These necessarily converge more or less, according to the difference of the width between 45 the bottom face, A, and the top face, B, and this convergence is necessarily greater toward the rear of the key.

Having thus described my invention, what I claim, and desire to secure by Letters Patent, is—

The design for a musical instrument key substantially as described and illustrated in the accompanying drawings.

In testimony whereof I affix my signature 55 in presence of two witnesses.

AUGUSTUS NEWELL.
